Emil Klahn Inventor
By his Attorney Paster Morton

UNITED STATES PATENT OFFICE.

EMIL KLAHN, OF WEST HOBOKEN, NEW JERSEY.

BALL-BEARING.

No. 799,008.

Specification of Letters Patent.

Patented Sept. 5, 1905.

Original application filed May 4, 1898, Serial No. 679,721. Divided and this application filed May 23, 1898. Serial No. 681,532.

To all whom it may concern:

Be it known that I, EMIL KLAHN, a citizen of the United States, and a resident of West Hoboken, in the county of Hudson and State of New Jersey, have invented certain new and useful Improvements in Ball-Bearings, of which the following is a specification.

My invention relates especially to improvements in ball-retaining devices for ball-bearings; and it has for its object the provision of a simple and effective device by which the balls in a bearing may be kept separate and the friction due to the rubbing of the balls upon one another prevented.

15 The above object is obtained by the constructions shown in the accompanying drawings, in which—

Figure 1 is a view of a blank for making a ball-retaining device. Fig. 2 is a plan view 20 of a ball-retainer formed from a blank of the kind shown in Fig. 1 and supplied with a full complement of balls. Fig. 3 is a view in section upon the line 3-3 of Fig. 2. Fig. 4 is a plan view of a somewhat different form of ball-retaining device supplied with balls. Fig. 5 is a plan view of the blank from which the ball-retaining device shown in Fig. 4 is formed. Fig. 6 is a sectional view on the line 6-6 of Fig. 4. Fig. 7 is a view of a hub with one 30 end in section, showing the ball-retaining device illustrated in Figs. 4, 5, and 6 as applied to a ball-bearing.

Similar characters of reference indicate corresponding parts in the several figures.

35 Figs. 1, 2, and 3 are copied from my prior patent, No. 611,689, granted October 4, 1898.

Referring to the drawings, A designates a ring-shaped base of sheet metal, which is shown in the drawings as concave and is provided at its outer margin with projecting flaps *a*, which are radially arranged and are spaced at substantially equal distances apart, as shown. The flaps *a*, which are adapted to be bent upwardly, so as to stand substantially at right angles to the plane of the base and form standards, are provided with extensions *b*, the opposite sides of which are scalloped or inwardly curved. The extensions *b* are designed to be bent so as to overhang the base and lie substantially parallel thereto when the flaps are bent upward to form standards.

In Figs. 4, 5, and 6 I have illustrated a ball-retaining device having a ring-shaped concave base A', of sheet metal, from the inner margin 55 of which extend flaps *a'*, which are spaced at equal distances and extend toward the center of

the ring-shaped base. The flaps *a'* are designed to be bent upwardly, as shown in Fig. 6, to form standards, and they are provided with flaring or laterally-enlarging extensions *b'*. These 60 flaring or laterally-enlarging extensions *b'* are designed to be bent to overhang the base, as shown in Fig. 6, and to lie substantially parallel with the plane of the base.

In both forms of ball-retaining device above 65 described the standards and extensions thereof coöperate with the base to create spaces into which balls B may be sprung without difficulty, the standards and extensions yielding sufficiently to permit the balls to be sprung 70 or snapped into the spaces. When the balls are in position in the spaces presented by a retainer of either form, they will be effectively held against displacement, but they will be permitted to rotate freely, and each ball will 75 be kept out of contact with others. The ball-retaining devices of either type are applied to ball-bearings, as shown in Fig. 7. One of the ball-retaining devices with its complement 80 of balls is placed in one of the ball-cups C of the hub, and the corresponding cone D is then screwed upon the end of the shaft E until proper adjustment is obtained. The cones of the bearings can rotate within the cups or the cups can turn on the cones, as the case 85 may be, without interference with or from the ball-retaining devices.

In Fig. 7 only one end of the hub is shown as provided with a ball-retaining device. If a ball-retaining device be used in the other 90 end of the hub, it will be placed in precisely the same position, and additional description seems unnecessary.

It is a well-known fact that in the common ball-bearing a considerable amount of friction 95 is frequently due to the rubbing of the balls upon one another. Such friction cannot occur in ball-bearings equipped with the improved ball-retaining devices.

It will be noted that the ball-retaining devices shown and described are characterized by concave ring-shaped bases. The concave form of the bases adds materially to their rigidity, as will be obvious, and prevents the distortion of the base except when subjected 100 to violent strains.

Having thus described my invention, I claim as new and desire to secure by Letters Patent—

1. A ball-retaining device for ball-bearings, consisting of a ring-shaped portion or base 110 having a series of spaced standards rising at one margin only of the base and having their

- free ends extended to overhang the base, said free ends being so formed that suitable spaces are presented for receiving and confining balls without preventing free rotation of the balls.
- 5 2. A ball-retaining device for ball-bearings, consisting of a ring-shaped portion or base and a series of spaced standards rising at one margin only of the base, the base being concave and the standards having their free ends 10 extended to overhang the base, the free ends of the standards being so formed that suitable spaces are presented for receiving and confining balls without preventing free rotation of the balls.
- 15 3. A ball-retaining device for ball-bearings, consisting of a ring-shaped portion or base and a series of spaced standards rising at one margin only of the base, the base being relatively stiff and the standards relatively elastic and having their free ends extended to 20 overhang the base, said free ends being so formed that suitable spaces are presented for receiving and confining balls without preventing free rotation of the balls.
4. A blank for making a ball-retaining device for ball-bearings, consisting of a ring-shaped portion and a plurality of inwardly-disposed flaps or extensions which are flaring or sector-shaped at their free ends.

Signed at New York, in the county of New 30 York and State of New York, this 16th day of May, A. D. 1898.

EMIL KLAHN.
